(57) **CLAIM**

The ornamental design for a mood monitoring device, as shown and described.

DESCRIPTION

FIG. 1 is a perspective view showing my new design;

FIG. 2 is a front elevation view;

FIG. 3 is a rear elevation view;

FIG. 4 is a top plan view;

FIG. 5 is a bottom plan view;

FIG. 6 is a right side elevation view;

FIG. 7 is a left side elevation view;

FIG. 8 is a front elevation view of a second embodiment;

FIG. 9 is a front elevation view of a third embodiment;

FIG. 10 is a front elevation view of a fourth embodiment;

FIG. 11 is a perspective view showing the embodiment in FIGS. 1-7 in use;

FIG. 12 is a perspective view showing the embodiment in FIGS. 1-7 in use; and,

FIG. 13 is a perspective view showing the embodiment in FIGS. 1-7 in use.

The broken lines in the drawing are for illustrative purposes only and form no part of the claimed design.
